DISH DRAINER

Paul H. Planeta, East Hampton, Conn.

Application February 7, 1952, Serial No. 18,424

Term of patent 14 years

(Cl. D44—29)

To all whom it may concern:

Be it known that I, Paul H. Planeta, a citizen of the United States, residing at East Hampton, in the county of Middlesex, State of Connecticut, have invented a new, original, and ornamental Design for a Dish Drainer, of which the following is a specification, reference being had to the drawing, forming a part thereof.

Fig. 1 is a perspective view of a dish drainer showing my new design;

Fig. 2 is a top plan view thereof; and

Fig. 3 is a side elevational view thereof.

I claim:

The ornamental design for a dish drainer, as shown.
